UNITED STATES PATENT OFFICE.

CHARLES A. HAWLEY, OF DENVER, COLORADO.

DESIGN FOR A BADGE.

SPECIFICATION forming part of Design No. 17,839, dated October 25, 1887.

Application filed July 20, 1887. Serial No. 244,835. Term of patent 3½ years.

To all whom it may concern:

Be it known that I, CHARLES A. HAWLEY, a citizen of the United States, residing at Denver, in the county of Arapahoe and State of Colorado, have invented and produced a new and original Design for Badges; and I do declare the following to be a full, clear, and exact description of the invention, such as will enable others skilled in the art to which it applies to make and use the same, reference being had to the accompanying drawing, and to the letters and figures of reference marked thereon, which form a part of this specification.

The accompanying drawing illustrates in front view a badge made in accordance with my design.

My design consists of a heart-shaped shield having a roughened face with a plain border. In the upper portion of the shield there is a raised five-pointed star having a smooth surface, and upon this star there is formed in bas-

relief a representation of the head of George Washington.

I am aware that in heraldic insignia shields having stars and other figures on them are common. I therefore make no broad claim to such designs.

What I claim is—

The herein-described design for a badge, consisting of a heart-shaped shield having a roughened face and an ornamental border, a five-pointed star having a plain face, and a representation of the head of George Washington on said star, both the star and head being in bas-relief, as shown.

In testimony whereof I affix my signature in presence of two witnesses.

CHARLES A. HAWLEY.
